UNITED STATES PATENT OFFICE.

THOMAS FLEMING, OF OTTAWA, ONTARIO, CANADA.

DOOR-OPERATING MEANS.

Application filed November 11, 1924. Serial No. 749,168.

The present invention appertains generally to the art of door operating means and specifically to a power operated mechanism adapted for opening and closing heavy doors such as used upon garages and similar buildings.

It has been proposed to open and close doors by a mechanism including a guide-way mounted upon an overhead support, which 10 serves to guide a crosshead operatively connected to hinged doors, said crosshead being reciprocated by motive power. In other mechanisms in the art, it has been proposed to employ rotatable crank arms operatively 15 connected to doors. Furthermore, it has been proposed to hinge doors upon vertical rods or pintles which are turned by motive power to effect opening and closing of doors.

To use mechanism constructed in accordance with what has been disclosed in the art, it is essential to connect the connecting rods of the device in close proximity to the door pintles or hinging point, in view of the fact that only a short reciprocation 25 is obtainable of using crank arms and equivalent means, as has been taught, and incidentally only doors of the smaller and medium sizes may be operated at the required speed, unless unreasonably large 30 motors are used.

In addition, one of the principal factors so subversive of the efficiency of the mechanism heretofore devised is that the same is not adapted for use in very restricted areas 35 to operate large heavy doors, as is oftentimes essential in garages, machine shops and other buildings where overhead shafting, machinery or other obstructions would prevent installation of the mechanism.

Cognizant of the foregoing general inadequacies of design, one of the principal objects of my invention is to provide a compact and durable mechanism which may be operated with the minimum power and 45 which will serve to open and close doors expediently, irrespective of their size and weight, consistent with the purpose of the invention.

A further object of my invention is to provide a mechanism embodying the aforesaid characteristics of construction including a guide-way upon which a crosshead is constrained for longitudinal reciprocation and to which a movable closure is connected by 55 appropriate means, said crosshead being re-

ciprocated by a motor driven drum through the medium of a flexible cable trained thereabout and over guide pulleys mounted at the extremities of said guide-way, and connected to the opposite ends of said crosshead so 60 that said crosshead is free to reciprocate the entire length of said guide-way or between predetermined intermediate points, according to the extent of the reciprocation required. 65

A further object of my invention is to provide a two-way four-pole switch operated by a switch operating member extending longitudinally of said guide-way, said member being provided with fingers adapted to 70 be abutted by a finger carried by said crosshead, said fingers on said switch operating member being adjustable so that any required extent of reciprocation, for the purpose of opening and closing doors, may be 75 obtained.

A further object of the invention is to provide means of the character described for opening a door or doors, co-operating with toggle mechanism connected to said doors 80 and to a stationary support, so that the maximum amount of force may be applied to the doors for opening and closing purposes.

In addition, the mechanism is susceptible 85 of adjustment to accommodate for doors of different widths and weights and to effect the door opening and closing operations in the minimum time.

With the foregoing and other objects in view as will appear as the description proceeds, the invention consists in the novel construction, combination and arrangements of co-operating elements as hereinafter more specifically set forth, claimed and shown in 90 the accompanying drawings forming a part of the present application and in which:

Fig. 1 is a plan view illustrating the application of my invention to a garage, the doors thereof being shown in closed position 100 in full lines and in open position in dotted lines, the mechanism being shown partly in section and on a reduced scale, as it would appear when taken on the plane designated by the line 1—1 on Fig. 2.

Fig. 2 is a side elevation of the mechanism, the same being drawn at a larger scale than Fig. 1, parts being broken away and shown in section.

Fig. 3 is a transverse vertical sectional 110

elevation as it would appear when taken on the plane designated by the line 3—3 on Fig. 2, and

Fig. 4 is the wiring diagram.

5 The numerals 5 and 6 designate the side walls of a building, which for the purpose of the present disclosure will be hereinafter termed a garage, the same being provided with a front wall 7 having the usual opening therein to permit entrance of a motor vehicle and closure means therefor including a pair of hinged doors 8 and 9, hinged as at 10 and 11 to the front wall 7.

15 The machine constituting my present invention is adapted to be mounted upon an overhead support above the plane in which the tops of the doors 8 and 9, swing, and when conditions warrant, is preferably mounted upon the ceiling of a building.

20 For the purpose of illustration, the lines A—B in Figs. 2 and 3 designate a ceiling. A guideway formed of two angle beams 12 and 13 is braced beneath the ceiling by pairs of braces 14 and 15 and pairs of intermediate braces 16 and 17. The lugs 20 on the lower ends of the pairs of braces 14 and 15 are connected to the lugs 19 on the castings 18 by means of bolts 21. The upper ends of the pairs of braces 14 and 15 are provided 25 with lugs 22 through which bolts 23 may extend into the ceiling to secure said braces in position. The castings 18 which are riveted to the angle beams 12 and 13 as at 24, carry brackets 25 between which cable guide 30 pulleys 26 are rotatably mounted on the pins 27.

35 The crosshead 28, positioned on said guideway is provided with two aligned openings arranged at an acute angle with respect to the longitudinal axis of the crosshead to receive the drawbolts 29 and 30, best shown in Fig. 1. The ends of the cable 31 are connected to the looped ends of said drawbolts, and said cable, extends horizontally of the guideway, is trained over pulleys 26 and is wound tightly about the drum 32, best shown in Fig. 3.

40 The drum 32 is mounted upon a shaft 33 which is journaled in the brackets 34 and 35 integral with the base 36. A worm gear 37 is mounted upon the end of the shaft 33 and is rotated by a worm 38 mounted upon the shaft 39 of the motor 40.

45 The bolt which extends into the bottom of the crosshead 28 forms a pivotal connection for the connecting rods 42 and 43, the opposite ends of which are connected to the toggles 44 and 45 as at 46 and 47, said toggles being connected to the doors 8 and 9 in close proximity to the edges thereof as at 48 and 49, the other ends thereof being connected to brackets supported by the walls 5 and 6 as at 50 and 51.

50 A two-way four-pole switch 52 is mounted upon one of the brackets 16 and is pro-

vided with an arm 53 having a bifurcated extremity which straddles a stop-member 54 on the switch operating member 55. The switch operating member referred to extends longitudinally of the guide-way and is supported in bosses 56 through which it is free to reciprocate. Fingers 57 and 57' are adjustably positioned on said member 55 for the purpose of determining the extent of reciprocation of the crosshead 28 as herein-after more specifically set forth, the same being controlled by the finger 58 on the crosshead 28.

55 The two-way four-pole switch, designated in its entirety by the numeral 52 has six contacts 59, 60, 61, 62, 63 and 64. When the switch 52 is positioned as shown in Figs. 2 and 4, current travels through the wires 65 and 66, switch 67, wires 68, 69 and 70, through the knife 71 of the switch 52, wires 72, 73, 74 and 75. Current also travels through the knife 76 of the switch 52 and wires 77, 78 and 79. Current entering the wire 80 flows directly through wire 81 to the motor 40, and through the wire 82, the knife 83 of the switch 52 and the wires 84 and 85 and 86. When the two switches are reversed current flows through the wires 65 and 66, the switch 67, the wire 87, the knife 88 of the switch 52, and the wires 74 and 75. Current also flows from the contact 59 through the wire 73, the knife 76 of the switch 52 and through the wires 85 and 86. Current also flows through the wires 80 and 82, the knife 83 of the switch 52, and the wires 78 and 79, and also through the wires 80 and 81.

60 The operation of my device may be described as follows: To open the doors 8 and 9 the switch 67, which may be placed at a remote location with respect to the garage, such as in a residence or any other convenient location, is thrown so that current energizes the motor. The worm 38 meshing with the worm-gear 37 rotates the latter which in turn rotates the drum 32, which winds the cable 31 thereabout and draws the crosshead 28 upon the guideway in the direction indicated by the arrow A in Fig. 2. When the finger 58 of the crosshead strikes the finger 57' on the switch operating member 55, said member is moved in the direction indicated by the arrow A so that the stop member 54 will throw the arm 53 of the switch 52 to reverse the same and break the circuit to the motor, which incidentally stops. By a perusal of Fig. 1 it will be noted that advancement of the crosshead 28 will cause the toggles 44 and 45 to assume the positions shown in dotted lines in Fig. 1. From this view it will be noted that the doors have been swung completely open and out of the way of the vehicle which may enter or leave the garage.

65 To close the doors the switch 67 is reversed to energize the motor 40. The motor 40, now

rotating in a reversed direction, rotates the drum 32 so that the cable will draw the crosshead 28 along the guide-way in the direction indicated by the arrow B. When the 5 fingers 58 thereof strikes the finger 57, the switch operating member 55 is forced in the direction indicated by the arrow B which action throws the switch arm 53 of the switch 52 to the position shown in Fig. 2, thus 10 breaking the circuit and reversing the switch for the ensuing operation.

By utilization of the toggles 44 and 45 the maximum force may be applied to the doors 8 and 9 for closing purposes, as is readily 15 obvious, and by virtue of the structure which provides for reciprocation of the crosshead 28 substantially the entire length of the guide-way, the required extent of reciprocation may be obtained so that utilization 20 of the toggles in the manner described is made practical.

While I have illustrated the application of my invention for operating doors inwardly it is of course understood that the 25 same will operate with equal efficiency on doors that swing outwardly and where occasions demand may be used on double hinged doors or sliding doors without departing from the spirit of the invention.

30 Although the preferred embodiment of the invention has been described it is to be understood that minor changes in the details of construction, combination and arrangement of co-operating elements may be resorted to within the scope of what is claimed 35 without departing from the spirit of the invention.

What I claim as new is:

1. The combination with a movable closure, of a guide-way; a reciprocatable cross-head in said guide-way; means connecting said movable closure and crosshead, an elec-

tric motor-driven drum; a cable engaged thereby extending longitudinally of said guide-way over the ends thereof, and connected to said crosshead at opposite ends; a switch for controlling said motor; a switch operating member extending longitudinally of said guide-way engaging said switch; and means for engaging said crosshead and 50 switch operating member at the extent of predetermined reciprocation of said crosshead to reverse said switch.

2. The combination with a movable closure, of a guide-way; cable pulleys on the ends thereof; an electric motor-driven drum; a reciprocatable crosshead; means connecting said movable closure and said reciprocatable crosshead; a cable wound about said drum, extended longitudinally of said guide-way, trained over said pulleys, and connected to said crosshead at opposite ends; a reversible motor control switch; a reciprocatable switch operating member engaging said switch; fingers adjustable longitudinally 65 on said member; and means extending from said crosshead for abutting said fingers to throw said switch operating member and switch.

3. The combination with a door hinged to swing inwardly and a stationary support inwardly thereof; of a toggle connected to said door and stationary support; a reciprocatable crosshead; and a rod connecting said reciprocatable crosshead and toggle, to 75 open said door when said crosshead is moved in the opposite direction to the direction in which said door is opened and to close said door when said crosshead is moved in the opposite direction to which said door is 80 closed.

In testimony whereof, I affix my signature.

THOMAS FLEMING.
